UNITED STATES PATENT OFFICE.

GUSTAVE TRASENSTER, OF OUGREE-LEZ-LIEGE, BELGIUM, ASSIGNOR TO SOCIÉTÉ ANONYME D'UGREE-MARIHAYE, OF OUGREE-LEZ-LIEGE, BELGIUM.

BOILER FURNACE.

Application filed December 14, 1920, Serial No. 430,655, and in Belgium August 10, 1920.

The subject matter of the present invention is a water-tube boiler heated by a furnace using pulverized or non-pulverized coal, and designed with a view to ensuring a 5 complete combustion of this fuel. For this purpose, the boiler is divided, in so far as the course followed by the gases is concerned, into two communicating compartments, in the first of which the coal is burnt 10 by means of hot air and transformed into CO, which is burnt into CO₂ in the second compartment by hot air. This hot air is supplied by a heater.

The accompanying drawing shows a boiler 15 according to the present invention.

Figure 1 is a section taken substantially on the line 1—1 of Fig. 2 looking in the direction of the arrows.

Fig. 2 is a section on the line 2—2 of 20 Fig. 1.

Figure 3 is a section on the line 3—3 of Fig. 1.

The boiler shown consists of two drums 1 and 2, connected with each other by means 25 of vertical tubes 3 and 4, divided into two separate sets by the vertical partition 5, which forms two compartments 7 and 8, which are in communication with each other only from below.

30 The furnace includes burners 6 and 6' which are fitted at the top part of each of the compartments 7 and 8, the walls of which are fitted internally with baffles 9 designed to compel the gases and the air to circulate between the tubes 3 and 4.

35 The feeding of the boiler with water is effected by means of a pipe 10 leading to the bottom drum 2. It is advantageous to subject this water to preliminary heating, by 40 means of a flue gas economizer or similar apparatus 12, utilizing the hot gases issuing from the flue 14, previous to their escape through the chimney 13. The pipe 10 is placed in communication with the drum 1 by a pipe 15 controlled by a valve 11.

45 The level of the water in the top drum 1 is therefore regulated by the level in the heater 12, in such a way that an intense vaporization and circulation, as well as a continuous feeding with water, can be obtained.

The pulverized coal is injected into the first compartment 7 through the burners 6, and transformed by combustion into CO by means of hot air supplied in an insufficient 55 quantity to burn the fuel completely. The

gases descend in compartment 7, in a direction opposite to that of the circulation of water in the tubes 3, following the course formed by the baffles 9, and are delivered thru the conduit 20 to the burners 6' in the top of the chamber 8 where they are completely burned into CO₂, air being suitably supplied to the burners through pipes 6^a for this purpose. The products of this combustion pass downwardly thru chamber 8, thence out at the bottom and eventually into the chimney 13.

Having fully described my invention, what I desire to claim and secure by Letters Patent is:—

1. In a boiler furnace, in combination, a furnace housing, a partition dividing said furnace housing into two compartments, water tubes arranged in each compartment, a burner disposed at the top of the first compartment for burning fuel with a limited quantity of air therein, a flue for conducting the gases from the bottom of the first compartment to the top of the second compartment, a burner disposed at the top of said second compartment for burning the gases with an additional supply of air, and a flue for conducting the products of combustion away from the bottom of said second compartment.

2. In a boiler furnace, in combination, a furnace housing, a partition dividing said furnace housing into two compartments, vertical water tubes arranged in each compartment, baffles in said compartments for causing burning gases to travel from side to side across said tubes in passing through said compartments, a burner disposed at the top of the first compartment for burning fuel with a limited quantity of air therein, a flue for conducting the gases from the bottom of the first compartment to the top of the second compartment, a burner disposed at the top of said second compartment for burning the gases with an additional supply of air, and a flue for conducting the products of combustion away from the bottom of said second compartment.

3. In a boiler furnace, in combination, a furnace housing, a partition dividing said furnace housing into two compartments, vertical water tubes arranged in each compartment, a burner disposed in one end of the first compartment for burning fuel with a limited quantity of air therein, a flue for

conducting the gases from the end of the first compartment opposite the burner to one end of the second compartment, a burner disposed at the same end of the second compartment as that to which the flue leads for burning the gases with an additional supply of air, the circulation of water in said ver-

tical tubes being in an opposite direction in each compartment to the flow of burning gases, and a flue for conducting the products of combustion away from the end of said second compartment opposite the burner. 10

In testimony whereof I affix my signature.

GUSTAVE TRASENSTER.
